UNITED STATES PATENT OFFICE.

THOMAS HOWARD PEGRAM AND JOHN HENRY KESTER, OF WINSTON,
NORTH CAROLINA; SAID KESTER ASSIGNOR TO SAID PEGRAM.

CAR-COUPING.

SPECIFICATION forming part of Letters Patent No. 294,501, dated March 4, 1884.

Application filed June 4, 1883. (No model.)

To all whom it may concern:

Be it known that we, THOMAS HOWARD PEGRAM and JOHN HENRY KESTER, both citizens of the United States, residing at Winston, in the county of Forsyth and State of North Carolina, have invented certain new and useful Improvements in Car-Couplings; and we do hereby declare the following to be a full, clear, and exact description of the invention, such as will enable others skilled in the art to which it app pertains to make and use the same.

Our invention relates to that class of car-couplings in which the coupling-pin is caused to automatically drop through the draw-head and enter the coupling-link to couple the cars by the action of the cars coming together.

The object of this invention is to provide a simple and effective arrangement of devices whereby railroad-cars, especially freight-cars, may be automatically coupled and uncoupled without going between the same, thus preventing numerous accidents and loss of life resulting from the necessity of going between the cars and handling the coupling devices.

To this end, therefore, the invention consists of a band placed around the front portion of the draw-head and projecting slightly from the front edge thereof, to which is attached at each side rods for holding said band in position, and to form a means for holding suitable coiled springs, which act to keep the band projected in a forward position beyond the edge of the draw-head, this band acting to hold the coupling-pin in a vertically-suspended position, and as a means for automatically tripping the said pin and causing the coupling together of the cars upon the coming together of the draw-heads of the same, and also serving as a spring-buffer for the cars, as will hereinafter appear.

Referring to the drawings which form a part of this application, and in which similar letters of reference indicate like parts in the several views, Figure 1 represents a side elevation, partly in section, of two adjacent railroad-cars provided with our proposed improvement; Fig. 2, a central longitudinal sectional view of the same, showing the coupling-pin in a vertically-suspended position; Fig. 3, a plan, partly in section, with the cars as close together and the pin as about to drop into position.

Fig. 4 is a front elevation of the car with the coupling-pin as in its coupled position.

A A represent the adjacent ends of two railroad-cars, and B B the draw-heads thereof, secured in the usual or any approved manner to the frames of the cars. C is the coupling-pin, and D the link. Attached to the coupling-pin C by a link, e, is a bent or double-crank-shaped rod, E, which has its bearing upon the end of the car, as at F. This rod E has a right-angled bend or arm, e', at the sides of the car, by which to operate said rod and through it raise the coupling-pin, as will hereinafter appear. At the top of the draw-head, in front of the pin-hole C', is formed a recess or seat, c, for the coupling-pin. Around the front portion of the draw-head, sliding thereon, and projecting slightly from the front edge thereof, is a band, G, to which is attached at each side rods H H, which pass through guides h h, secured to the sides of the body of the draw-head, and have thereon, between said guides h h, coiled springs I I, which act to keep the band G projected in a forward position. At the top of the band is formed a head, G', having a hole, g, therethrough, through which passes the coupling-pin. This hole g is of an oval form, of a size slightly in excess of the diameter of the coupling-pin, for the purposes as will herein-after appear.

The operation of the parts is as follows: By raising the handles e' of the rod E, the coupling-pin is raised, and at the same time, because of the close connection between the end e' and the pin, the top end of the pin is carried back toward the car, which causes the pin to assume a slightly-inclined position and brings its lower end into the seat c, formed adjacent to the pin-hole of the draw-head. By this means the pin is raised and suspended in a vertical position, the oblong opening g' in the head G' of the band G permitting the pin to assume such an inclined position necessary to raise the pin and bring its end into the seat for the same on the top of the draw-head. As the cars approach together, the front edges of the band around the draw-head come together, and, not being rigidly secured in position, they are carried back until the faces of the draw-heads come flush together, which limits the movement of

said band or pin-tripping device. As this band recedes by the contact of the cars as they advance toward each other, the lower end of the coupling-pin, being held by the head or 5 enlargement of the band through which said coupling-pin passes, is also carried backward and over the pin-hole in the draw-head, into which it at once drops, and, passing through the coupling-link which had previously entered the mouth of the draw-head, couples the cars together. On the reverse movement of the cars the band is again driven forward by the spiral springs at its sides, the slot in the head of the band permitting this without reference 10 to the contact of the coupling-pin.

By the herein-described arrangement of parts a simple and effective means is produced for uncoupling railroad-cars without going between the same or handling the coupling-pin 15 and automatically coupling the same by the action of the cars themselves.

The hand-lever for operating the pin may be placed on both sides of the draw-head, if desired or found necessary.

25 By reason of the springs at the rear of the pin-tripper said pin-tripper partakes of the nature of a buffer and acts very successfully to lessen the jar and concussion incident to the cars coming together.

30 O, Fig. 3, is a lever pivoted at o to the end of the car, one end of which lever is made to extend to the side of the car and the other is connected to the band G. The object of this lever is to provide a means whereby the band 35 may be manipulated or forced forward and

backward by hand from the outside of the cars in case the springs I should be unable to drive the band forward because of accumulated ice, snow, or other obstruction.

Having thus fully described our invention, 40 the nature, objects, and advantages thereof, what we claim as new, and desire to secure by Letters Patent of the United States, is—

1. In a car-coupling, the combination of the draw-head B, having the seat c for the coupling-pin at its top portion, band G, encompassing or passing entirely around the front portion of the draw-head and projecting from the front edge of the same, guide-rods H, attached at each side of the band, and springs I, mounted upon said rods and acting to keep the band in a forward position, with the coupling-pin adapted by suitable means to be held in a vertically-suspended position above the pin-hole, substantially as and for the purposes described. 50

2. In a car-coupling, the combination, with the draw-head B, having seat c in its top portion, and band G, encircling the front portion of the draw-head and projecting from the front edge of the same, of the lever O, pivoted to the 60 end of the car, and attached to the band, whereby said band may be operated by hand at the side of the car, for the purposes set forth.

In testimony whereof we hereto affix our signatures in presence of two witnesses.

THOMAS HOWARD PEGRAM.
JOHN HENRY KESTER.
